UNITED STATES PATENT OFFICE.

GLENN PEACOCK, OF BARTLESVILLE, OKLAHOMA.

VACUUM ATTACHMENT FOR CLOTHES-PRESSING MACHINES.

Application filed April 11, 1921. Serial No. 460,277.

To all whom it may concern:

Be it known that I, GLENN PEACOCK, a citizen of the United States, residing at Bartlesville, in the county of Washington and State of Oklahoma, have invented certain new and useful Improvements in Vacuum Attachments for Clothes-Pressing Machines, of which the following is a specification.

10 This invention relates to pressing machines, and the primary object of the invention is to provide an improved means for removing the damp steam from the garments after the pressing and steaming operation, 15 so as to dry and set the garments, so that the same will hold their shape.

It is therefore another object of the invention to provide an improved suction attachment for the pressing machine embodying an electric motor operated fan for creating a suction in the buck for effectively removing the damp steam from the garment and for drying the same.

A further object of the invention is to 25 provide means connected with the fan for permitting the cleaning of the clothes by suction prior to the pressing operation, so as to permit the removing of loose lint and dust from the clothes, and thereby preventing 30 the matting thereof in the weave of the garment by the introducing of damp steam therein.

A still further object of the invention is to 35 provide a novel means for controlling the suction in the buck and the suction in the cleaning head, said means being controlled by a foot operated pedal.

A still further object of the invention is to 40 provide a suction attachment for clothes pressing machines, which is of exceptionally simple and durable construction, which can be added to machines already on the market or which can be associated therewith at the time of their manufacture.

45 With these and other objects in view, the invention consists in the novel construction arrangement and formation of parts as will be hereinafter more specifically described, claimed and illustrated in the accompanying

drawings, forming a part of this specification, in which drawings:

Figure 1 is a fragmentary front elevation of a pressing machine showing the improved suction attachment connected therewith, the front or pressing body of the machine being 55 shown in longitudinal section.

Figure 2 is a fragmentary end elevation of a pressing machine showing the improved suction attachment connected therewith.

Figure 3 is an enlarged fragmentary detail end elevation of a portion of the suction attachment and

Figure 4 is a fragmentary sectional view looking at right angles from Figure 3 showing a portion of the attachment in vertical 65 section.

Referring to the drawings in detail, wherein similar reference characters designate corresponding parts throughout the several views, the letter A indicates the improved suction attachment for the pressing machine B.

The pressing machine B is of the usual or any preferred construction and as shown 70 consists of the supporting base 5, the work table 6, and the pressing buck 7. The pressing buck 7 is mounted in the usual manner on the table 6 and base 5 and this buck is also of the usual or any preferred construction and as shown includes the perforated 80 press plate 8, the press cloth or pad 9. Below the perforated press plate 8, a horizontally disposed partition 10 is positioned and this partition 10 in connection with the perforated press plate 8 forms the internal suction chamber 11. This is the chamber in which the steam is usually permitted to pass through to form the suction.

The improved attachment A consists essentially of an operating device or prime 90 mover D, a suction operating mechanism E, and a suction pipe system F.

The prime mover D as shown, consists of an electric motor 15, which is secured to a suitable supporting base 16, which can be 95 secured in any preferred manner to the base or frame work 5. While I have shown an electric motor, it is to be understood that

any other suitable prime mover may be used. The lower surface of the table 6 may be provided with a suitable electric switch 17 for controlling the flow of current through the 5 feed wires 18 for the electric motor.

The suction creating means E comprises a fan casing 19, which can be bolted, by means of strap iron strips 20 to the frame of the motor 15, and this fan casing has rotatably 10 mounted therein the fan wheel 21 which can be keyed or otherwise secured to the armature shaft 22 of the motor 15. The fan 21 is of the type employed in vacuum cleaners and includes the fan wheel having the hub 23 and 15 the radially extending blades 24 which are cut inwardly at their hub portions, as at 25. The outer wall 26 of the fan casing is provided with a central inlet opening 27 which has communicating therewith a valve casing 20 28. The fan casing 19 may be provided with an air outlet 29 and a steam or condensation outlet 30.

The valve casing 28 forms a part of the suction pipe system F, and this valve casing forms a part of the three way valve construction, and as shown includes the vertically disposed body 31, which receives the rotatable plug 32. This plug 32 has the opposite sides thereof concave as at 33, and 25 is of a sufficient size to close the inlet opening 34 of the valve casing 31 when so desired. The opposite ends of the valve body 31 has secured thereto the upwardly extending suction pipe 37 and the downwardly 35 extending suction pipe 38. The upwardly extending suction pipe 37 has connection with a longitudinally extending suction pipe 40 by means of a T-joint 41 and the terminals of the longitudinally extending pipe 40 are 40 connected with the suction chamber 11 of the buck 7, by means of branch pipes 42 and 43. The lower end of the pipe 38 has connected thereto a flexible hose 44, which is provided with any preferred type of 45 suction cleaner nozzle 45, and it is to be understood that the clothes are adapted to be cleaned by the nozzle 45 prior to the pressing thereof so as to prevent the dust and lint being matted in the fabric. The 50 three way valve plug 32 is adapted to be closed so as to entirely close the port 34 or so as to connect the port 34 with the pipe 37 and to shut off the pipe 38 or to connect the pipe 38 to the port 34 and to shut off the 55 pipe 37 as clearly shown in Figure 4 of the drawings. If so desired, the condensation nipple 30 may have connected thereto a flexible hose 47 which may be led into the usual iron bucket 48 provided with the ordinary pressing machine. This construction entirely eliminates the necessity of leading the steam exhaust pipe to a point out of the building, which tends to weaken the steam vacuum in the usual pressing machine.

60 A foot pedal attachment G is provided

for operating the valve plug 32 and this mechanism consists of a lever 50 pivotally mounted intermediate its ends upon a suitable pivot pin 51 which is carried by the frame 5. The outer end of the lever 50 has 70 secured thereto a suitable foot pedal 52, while the inner end thereof has pivotally connected thereto a connecting rod 53 which is in turn pivotally connected to a crank 54, which is connected to the valve plug. It can be seen that it is merely necessary to press down upon the pedal 52 when it is desired to operate the valve. The valve is normally held in the position shown in full 80 lines in Figure 4 by means of a weight 55 which is slidably mounted upon the lever 50 inwardly of the pivot point 51.

The pressing machine is used in the ordinary manner and after the clothes have been pressed, the lever 50 is operated, so as 85 to permit the suction through the pipe 37 which will create a suction in the suction chamber 11, thus effectively sucking all of the damp steam from the clothes and effectively drying the same so that they will 90 hold their shape.

From the foregoing description, it can be seen that an improved device has been provided for pressing machines, which will permit the cleaning of the garments prior 95 to the pressing thereof, and which will effectively remove all of the damp steam from the garment without the use of the steam vacuum, thereby resulting in saving of time, labor and money.

Changes in details may be made without departing from the spirit or scope of this invention; but,

I claim:

1. The combination with a pressing machine including a buck having a perforated press plate, a suction chamber arranged below the press plate, of a suction creating means including a fan casing, a suction fan wheel arranged in the casing, an electric motor for operating the fan wheel, a suction chamber communicating with the inlet of said fan casing, a three way valve forming a part of said suction chamber, oppositely disposed pipes communicating with the 110 valve casing, a rotatable three way valve plug arranged in the casing, means connecting one of the pipes with the suction chamber of the buck, a crank arm connected to the valve plug, a lever pivotally mounted 115 intermediate its ends, a foot pedal formed upon the lever, a rod connected with the lever and the crank arm, a condensation pipe carried by the fan casing, and a receptacle carried by the pressing machine 120 for receiving said pipe.

2. The combination with a steam pressing machine including a buck having a suction chamber and a perforated press plate, of a suction creating means including a fan 130

chamber, having an outlet in its lower wall, and an exhaust outlet in one side wall adjacent the bottom wall, a suction fan in said casing, an electric motor for operating said fan, a suction casing communicating with the fan casing, a longitudinally extending pipe communicating with the opposite ends of the suction chamber in the buck, a pipe connected with the longitudinally extended pipe and the suction chamber, a flexible pipe leading from the suction chamber, and a three way valve for controlling the suction in the pipe connected with the longitudinally extending pipe and the flexible pipe. 10

GLENN PEACOCK.
